UNITED STATES PATENT OFFICE.

WALTER KENNEDY, OF CLIFF SIDE, NEW JERSEY.

GAS HEATER.

Application filed February 8, 1923. Serial No. 617,792.

My invention relates to improvements in gas heaters, and more particularly has reference to a portable circular type of heater of artistic design, which may be conveniently assembled or taken apart, and may be conveniently shifted when desired.

In the accompanying drawings, I have illustrated in Fig. 1 in front elevation, a heater embodying an application of my invention, parts being broken away. Fig. 2 is a section looking from right to left on the line 2—2 of Fig. 1. Fig. 3 is a plan view looking down upon the upper part of the burner. Fig. 4 is a front view of the burner. Fig. 5 a view from right to left at Fig. 4. Fig. 6 a longitudinal section of the burner. Fig. 7 a cross-section on the line 7—7 of Fig. 6. Fig. 8 is a front elevation on a reduced scale of the radiant. Fig. 9 is a section on the line 9—9 of Fig. 8. Fig. 10 is a section on the line 10—10 of Fig. 8. Fig. 11 is a cross-section of part of the grill looking from right to left at the same when mounted in the heater.

12 indicates a suitable form of standard terminating in a rectangular portion 13 at the top which is open at the back as indicated at 14. Said standard is provided with suitable flanges such as 15 which serve to support the metallic ring or frame 16 and which may be secured thereto by any suitable means such as the screws 17 as shown. The base of the ring is looped up in U-shaped formation as indicated at 18 to provide clearance for the burner 19, said burner being illustrated to better advantage in Figs. 3 to 7 inclusive, and being secured in the ring or frame 16 by flanges with screws such as 20. The burner it will be observed is curved conforming to the circle of the heater and is provided with a grid comprising two sections 21, 22, said sections being held together by any suitable means such as the screws 23. 24 indicates a sheet metal piece adapted to engage the groove 25 thus closing the bottom of the burner and forming a housing within which the air and gas mixes prior to combustion. The tubular part 19 of the burner terminates at the back adjacent the inlet plug 26 through which the gas passes from the coupling 27 upon which a flexible tube may be secured, and 28 indicates a three-legged spider attached to the framework of the heater as shown for supporting the coupling 27 and tip 26.

29 indicates a radiant of suitable refractory material which is corrugated on the front face as shown, the depth of the corrugations such as 30 being greater at the top than at the bottom, thereby increasing the area of radiant in the path of the flame as the top of the same is approached, and the said radiant is preferably cut away at the top as indicated at 31 to allow for escape for the products of combustion. The back of the radiant is also preferably provided with ribs or enlargements such as 31', thereby leaving an air space between the radiant and the next refractory heat insulating slab such as 32 which is also preferably provided with similar enlargements or ribs providing air space between it and the high temperature insulating slab or block 33 through which a channel 34 is also cut at the top communicating with the channel 31 in the radiant and providing for ventilation, the top of the frame 16 being also cut away over the channel 34 for the escape of the gases as indicated at 35.

36 is another metallic ring or band with a flange 37 at the back within which may be retained the metal disc 38 thereby closing the back of the heater, screws or bolts such as 39 serving to retain said band to the ring 16. 40 indicates an escutcheon or plate with an opening through which the products of combustion pass out. 41 indicates the grill of fire clay or other suitable material through which the radiant is exposed and said grill is retained against the ring 16 by any suitable means such as the cleats 42 which may be turned upon screws or pins 43. At the front of the heater a frame or ring 44 may be secured by any suitable means such as screws 45 which pass through the tube or bushing 46 between the frame 44 and ring 16 and into the frame 16, as shown to better advantage in Fig. 2.

46' indicates a circular flange around the upper part of the front of the radiant 29 adapted to fit within the flange 47 of the ring 16.

Of course it will be understood that various modifications may be made in the construction and arrangement of parts without departing from the spirit of the invention as claimed.

I claim:

1. In a heater of the class described, a heat radiating element substantially circular upon

- its horizontal axis, a burner adjacent the lower front of said element, said burner at its outlet curved substantially in conformity with the curvature of said element. 55
5. In a heater of the class described, a heat radiating element substantially circular upon its horizontal axis, a burner adjacent the lower front of said element, said burner adapted to discharge a greater quantity of 60 gas as the center thereof is approached from its opposite ends. 10
6. In a heater of the class described, a heat radiating element substantially circular upon its horizontal axis, a burner adjacent the lower front of said element, said burner partly circular upon its horizontal axis and adapted to produce a flame having an upper edge representing a curve of greater radius than the curve of said burner. 65
7. In a heater of the class described, a heat radiating element substantially circular upon its horizontal axis, a burner adjacent the lower front of said element, said burner at its outlet curved substantially in conformity with the curvature of said element and a substantially circular grill in front of said element and burner. 70
8. In a heater of the class described, a heat radiating element substantially circular upon its horizontal axis, a burner adjacent the lower front of said element, said burner at its outlet curved substantially in conformity with the curvature of said element and a substantially circular grill in front of said element and burner. 75
9. In a heater of the class described, a circular outer framework, a curved burner at the front and at the base of the same, a radiant immediately behind said burner and heat insulating material back of said radiant, said radiant having vertical corrugations deeper at the top than at the bottom. 80
10. In a heater of the class described, a circular outer framework, a curved burner at the front and at the base of the same, a radiant immediately behind said burner and heat insulating material back of said radiant, said radiant having vertical corrugations deeper at the top than at the bottom, and an air space between said radiant and said heat insulating material. 85
11. In a heater of the class described, a circular outer framework, a curved burner at the front and at the base of the same, a radiant immediately behind said burner and heat insulating material back of said radiant, said radiant having vertical corrugations deeper at the top than at the bottom, and an air space between said radiant and said heat insulating material. 90
12. In a heater of the class described, a circular outer framework, a curved burner at the front and at the base of the same, a radiant immediately behind said burner and heat insulating material back of said radiant, said radiant having vertical corrugations deeper at the top than at the bottom, and an air space between said radiant and said heat insulating material, and means for supplying gas at the back of said heater. 95
13. In a burner of the class described, a circular outer framework, a curved burner at the front and at the base of the same, a radiant immediately behind said burner and heat insulating material back of said radiant, said radiant having vertical corrugations deeper at the top than at the bottom, and an air space between said radiant and said heat insulating material, and means for supplying gas at the back of said heater, said heater having a standard immediately beneath the 100 centre of said burner. 100

In testimony whereof I hereunto affix my signature.

WALTER KENNEDY.
